UNITED STATES PATENT OFFICE.

CHARLES E. KETCHAM, OF FAIRPORT, VIRGINIA.

HAMMOCK-SUPPORT.

SPECIFICATION forming part of Letters Patent No. 240,522, dated April 26, 1881.

Application filed March 19, 1881. (No model.)

To all whom it may concern:

Be it known that I, CHARLES E. KETCHAM, of Fairport, Northumberland county, Virginia, have invented certain Improvements in Hammock-Supports, of which the following is the specification.

My invention is a portable support for hammocks, garden-tents, &c., constructed as fully described hereinafter, so as to constitute a rigid and substantial support for the hammock or other object, and yet capable of being folded to a compact shape for stowage or transportation.

In the drawings, Figure 1 is a perspective view of the support arranged for use. Fig. 2 is a side view, showing the adjustment of parts when the support and hammock are to be moved from place to place. Fig. 3 is a perspective view of the device folded for transportation.

The support consists, essentially, of the main strip A, feet B B, and standards C C.

The strip A consists of two or more sections, a, connected by a hinge, b, which permits the sections to be folded together or brought into line, as shown in Figs. 1 and 2, in which case they are secured by a bolt, c, or other retainer.

Each foot B is pivoted by a bolt, e, so that it may be turned transversely to the bar A, as shown in Fig. 1, or parallel thereto, as in Figs. 2 and 3.

Each standard C is pivoted at y to one section of the bar A, so that it may be turned to an upright or diagonal position, as in Figs. 1 and 2, or folded down upon the bar, as in Fig. 3. A section of each standard C is cut therefrom and hinged thereto, so as to form a brace, d, which, when folded up, will not exceed the dimensions of the bar C, Fig. 3, but when turned down, with its end resting in a socket, x, of the bar A, will prevent the standard from being folded down under the strain imposed by a hammock, I, suspended at the ends to staples f of the standards, or otherwise.

The feet B B, when turned transversely to the bar A, are secured by stays g, in the form of hooks, which may be hung to the standards C, or to detachable rings w, slipped over said standards, their ends catching in staples i on the feet, as shown in Fig. 1. When thus arranged the posts are in position to support

the hammock, awning, or tent secured in any suitable manner, the feet B B constituting a wide base, which will prevent the structure from upsetting, and the braces d holding the standards in place.

If necessary, a ridge-pole, E, adapted for connection to the standards, may be used either to brace the latter, or as a support for the awning, or for a net, or for a frame supporting the awning or net. In some instances such pole may be secured to adjustable supports, as shown in dotted lines, Fig. 1.

When the hammock is to be moved from place to place—for instance, from one room to another—the feet B B are turned parallel to the bar A, as shown in Fig. 2, thus permitting the device to be carried through contracted passages.

When the device is to be stowed or transported the ridge-pole and hammock and rings w are detached, the braces d folded into the recesses of the standards, the latter turned down upon the bar A, the feet turned parallel to the bar, and the sections of the latter folded together, as shown in Fig. 3, thus bringing the latter to a most compact and convenient form for transportation without interfering in the least with its capacity to be readily unfolded and erected.

If desired, the device may be made extensible, to fit it for use with hammocks of different sizes, by the use of means for extending one or both sections, a, of the bar A. Thus a section may be divided and the ends overlapped and slotted and connected by bolts h, as shown in Fig. 1; or a tongue, m, of a part of one section may extend into the other's hollow portion p of the section, as in Fig. 2, a nut, s, serving to secure the parts after adjustment. In like manner one or both sections of the ridge-pole E may be extensible, as may the standards and feet, as shown.

I do not confine myself to the above-described mode of constructing and arranging the braces d, as they may be differently connected—for instance, they may be hinged to the bar A.

When the device is used for tent purposes the standards C may be vertical.

I claim—

1. The combination of the single bar A, consisting of hinged sections and locking devices,

the feet B B, pivoted to the bar-sections, so as to turn either parallel or transverse thereto, the standards C, hinged at the ends to said sections, and the folding braces d, substantially as set forth.

2. The combination of the folding and extensible bar A, feet pivoted to turn transverse thereto, and folding standards C, and folding braces d, adapted to recessed parts of the standards, substantially as specified.

3. The combination, with the folding bar A, feet B B, and standards C, of the detachable ridge-pole E, substantially as set forth.

In testimony whereof I have signed my name to this specification in the presence of two 15
subscribing witnesses.

CHARLES E. KETCHAM.
